(57) **CLAIM**

The ornamental design for an audio receiver, as shown and described.

DESCRIPTION

FIG. 1 is a perspective view of an audio receiver showing my new design;

FIG. 2 is a top plan view thereof;

FIG. 3 is a side elevational view thereof, the opposite side elevational view being substantially a mirror image thereof;

FIG. 4 is a front elevational view thereof; and,

FIG. 5 is a rear elevational view thereof.

1 Claim, 2 Drawing Sheets**FIG. 1**

FIG. 2

FIG. 3**FIG. 4****FIG. 5**
